CHILD'S PRAM SUIT OR THE LIKE

Rose Taisch Friedman, Scranton, Pa.

Application September 9, 1952, Serial No. 21,395

Term of patent 7 years

(Cl. D3—17)

To all whom it may concern:

Be it known that I, Rose Taisch Friedman, a citizen of the United States of America, residing in Scranton, county of Lackawanna, and State of Pennsylvania, have invented a new, original, and ornamental Design for a Child's Pram Suit or the like, of which the following is a specification, reference being had to the accompanying drawing, forming part thereof,

Fig. 1 is a front view of a child's pram suit or the like showing my new design.

Fig. 2 is a rear view thereof.

Fig. 3 is another front view of the child's pram suit shown in Fig. 1 as it appears with the panel in partially opened position, and

Fig. 4 is a fragmentary view of the end of one of the sleeve cuffs as it appears in unbuttoned position.

I claim:

The ornamental design for a child's pram suit or the like, substantially as shown.

ROSE TAISCH FRIEDMAN.
